UNITED STATES PATENT OFFICE.

FRANK S. IRVINE, OF HUNTINGTON, NEW YORK, ASSIGNOR TO WESTERN ELECTRIC COMPANY, INCORPORATED, OF NEW YORK, N. Y., A CORPORATION OF NEW YORK.

MESSAGE-REGISTER SYSTEM.

Application filed November 24, 1922. Serial No. 602,948.

To all whom it may concern:

Be it known that I, FRANK S. IRVINE, a citizen of the United States, residing at Huntington, in the county of Suffolk and 5 State of New York, have invented certain new and useful Improvements in Message-Register Systems, of which the following is a full, clear, concise, and exact description.

This invention relates to message register 10 systems for telephone exchanges and more particularly to message register systems for use in telephone exchanges employing party line working wherein each of the stations of the party line is provided at the central office with a message register for registering calls.

An object of the invention is to provide an improved circuit arrangement for use in systems of this nature for selectively associating 20 with the calling station of a party line the message register individual thereto and for subsequently operating said register.

Another object of the invention is an improved arrangement for preventing the registration of calls upon the party lines which are in an unstandard condition.

To attain the objects of the invention, each station of the party line is provided with a certain test condition and the first selector 30 of a train of selector switches, employed for extending a connection from the calling line, is provided with testing means for determining which station of the party line is calling. The testing means controls the actuation of 35 a switching device associated with the calling line, which in turn controls the inclusion of the message register corresponding to the calling line in the message register circuit. This organization provides an improvement 40 over a circuit arrangement shown in a patent to D. M. Taggart and F. J. Scudder, 1,513,351, issued Oct. 28, 1924, wherein the switching device is not individual to the calling line.

45 A feature of the invention is a circuit arrangement in which the circuit of a message register is controlled at contacts of a cut-off relay regardless of the nature of the line with which the cut-off relay is associated. 50 If the call is successful, the register is operated to charge the call. If the calling line is in an unstandard condition by reason of a stray ground on either conductor of the

line, the testing means operates at this time, prevents the charging of the call and causes 55 the operation of an alarm device.

The invention may be more readily understood by reference to the following description considered in connection with the accompanying drawings, in which Fig. 1 shows 60 one of a group of two-party lines for use in a full mechanical office. Figs. 2, 3 and 5, when taken together, show the circuits of a line finder having access to the subscriber's line shown in Fig. 1, the circuits of a district selector switch, a sender finder and so much of an office sender as is necessary for an understanding of the invention; Fig. 4 includes a schematic showing of an incoming selector switch, a final selector switch and 65 a subscriber's line to which the final selector switch has access. The several figures of the drawing should be arranged with Fig. 1 to the left, Figs. 2, 3 and 4 in consecutive order to the right of Fig. 1, and Fig. 5 below 70 Fig. 3.

The calling line is provided with two substations each equipped with a transmitter, receiver and a call bell, and since the line terminates in a full mechanical office, each 75 substation is provided with an impulse dial. The two substations differ from each other in that at one substation the call bell is connected from ground to the ring conductor of the line through a condenser when the receiver is on its switchhook, and from ground to the tip conductor through one winding of the induction coil when the receiver is off the switchhook, whereas at the other substation the call bell is at all times connected from 80 ground to the tip conductor of the line through a condenser. The substation on called line C, Fig. 4, is of the usual type.

The calling line terminates in a line finder 85 switch of the well-known power driven panel type. The brushes of the line finder are connected to the circuit of a district selector switch. Associated with each of the substations A and B, connected to the calling line, is a message register. Associated with the calling line is a cut-off relay, which controls the extension of a common operating circuit extending through a brush of the line finder switch to the message registers.

The district selector, incoming selector

- and final selector switches shown in Figs. 3 and 4 are of the general type shown and described in the patent to Craft and Reynolds, 1,123,696, issued January 5, 1915.
- 5 Each of these switches has a vertically disposed switch shaft provided with five sets of brushes, each brush set having access to a bank of one-hundred terminals. For driving the switch shaft upwardly, an updrive magnet is provided, which, when energized, presses the switch shaft against a constantly rotating power drum, and for restoring the switch shaft to normal position, a down-drive magnet is provided, which, when energized, presses the switch shaft against a second constantly driven drum. For determining the particular set of brushes on the switch shaft to be employed, a tripping spindle is provided as described in the patent hereinbefore referred to. The circuits of the incoming selector switch and the final selector switch may be of the type described in the patent to D. M. Taggart, et al., hereinabove mentioned.
- 25 The steering switch RS, shown in Fig. 2, and the sender finder switch FS, shown in Fig. 3, are of the well-known step-by-step type, the wipers of which are advanced by a stepping magnet. The switch RS functions during a complete half revolution and upon the termination of a connection is left with its wipers in normal condition for serving on a new call. The wipers of finder switch FS have no normal contacts, the wipers resting in contact with the bank terminals last employed by the switch when the switch is not being employed.
- 40 The office sender has been only partially disclosed in Fig. 5, only such portions of the sender being disclosed as are considered necessary for an understanding of this invention. The circuits of a complete office sender are disclosed in Patent No. 1,395,977 to F. A. Stearn and F. J. Scudder, of November 1, 1921.
- 45 For controlling the circuits associated with the several selector switches and the circuits of the office sender, auxiliary switches are provided. These switches may be of the type described in the patent to Reynolds, et al., 1,127,808, issued February 9, 1915, and known in the art as sequence switches. Each sequence switch comprises a rotatable shaft driven from a constantly operating source of power through a magnetic clutch member and carries a plurality of circuit closing cams which at different radial positions of the shaft, cause the closure of a plurality of contacts. The cam contacts associated with each sequence switch are closed only in the positions indicated by the numerals, with the exception of the master contacts 301, 401 and 551 associated, respectively, with the switches 300, 400 and 550, these latter contacts being

opened in positions indicated by the numerals appearing adjacent such contacts and closed in all other positions.

The different pieces of apparatus employed in the system having now been briefly described, it is thought that a clearer understanding of the invention may be had from a description of the method of establishing a call. It will first be assumed that the subscriber at substation A desires connection with a line at substation C and that the directory number of the desired subscriber is LISpenard 9532.

Upon removal of the receiver from the switchhook at the station A, a circuit is established for line relay 102 over a path including grounded battery, winding of relay 102, outer left-hand armature and back contact of relay 103 through the loop of the calling station, back contact and inner left-hand armature of relay 103 and ground. The line relay 102 becomes energized in this circuit and completes a circuit for the group relay 104, common to all lines in the A subgroup of this particular brush group, to ground at the inner armature and contact of relay 102. Relay 104 becomes energized and completes a circuit from ground through its armature and contact, contact and armature of relay 105, left-hand armature and back contact of relay 106 and left-hand winding of relay 107 to grounded battery. Relay 107 operates in this circuit and in attracting its right-hand armature completes a locking circuit for itself and an energizing circuit for relay 218, said circuit extending over a path including grounded battery, winding of relay 218, conductor 124, right-hand armature, front contact and right-hand winding of relay 107 to ground. Relay 107, in attracting its outer left-hand armature completes an obvious circuit for operating the tripping magnet 213. Tripping magnet 213 rotates its tripping spindle 212. The tripping spindle in its rotated position prepares for the tripping of the set of brushes on the particular finder switch that is started in operation to find the calling line.

Relay 218, in operating, completes a circuit for relay 299 over a path including grounded battery, right-hand winding of relay 299, back contact and outer right-hand armature of relay 298, back contact and right-hand armature of relay 294 and contact and armature of relay 218 to ground. Relay 299, in operating, locks over a path including grounded battery, right-hand winding, front contact and inner left-hand armature and left-hand winding of relay 299, and ground at the back contact and armature of relay 214. Relay 299 in attracting its outer left-hand armature completes a circuit for the updrive power magnet 216 over a path including segment 295

125

130

and ground at brush 282. Power magnet 216 causes the upward movement of the brush shaft (not shown) whereby the desired brush set, including brushes 204 to 207 inclusive, are tripped into operative engagement with the terminals of the bank. Following the tripping operation the contact 287 is momentarily closed and a circuit is established from ground over said contact, 10 conductor 125, inner left-hand armature and front contact of relay 107 and the winding of relay 106 to grounded battery. Relay 106 attracts its armatures and locks in a circuit including battery, winding front contact and left-hand armature of relay 106, armature and back contact of relay 105 and ground at the contacts of relay 104. Relay 106, in attracting its right-hand armature closes a circuit for the right-hand winding 20 of relay 105. This winding is wound so that sufficient flux is not produced to cause the operation of relay 105. The right-hand winding of relay 105, however, maintains the armature of said relay attracted when it 25 has been operated by the left-hand winding. Relay 299, in attracting its outer left-hand armature also completes a circuit for relay 325, said circuit including ground at brush 282, segment 295, front contact and outer left-hand armature of relay 299, inner right-hand armature and back contact of relay 296, and grounded battery at the left-hand winding of relay 325. Relay 325 operates in 30 this circuit and locks over a path including battery, right-hand winding of relay 325, left-hand contact of sequence switch spring 308 (1+10), outer right-hand armature and front contact of relay 325 and ground at the wiper 391 of the sender finder FS provided 35 the arm 391 is standing on the test terminal of a busy sender. The operation of the sender finder FS will be described hereafter. Relay 325 in operating completes an obvious circuit through its inner left-hand contacts 40 for operating relay 394.

As the brushes 204 to 207 inclusive of the switch LF- are moved upwardly, brush 281 comes into engagement with segment 284 and completes a circuit for relays 294 and 50 296, said circuit extending over a path from ground through brush 281, segment 284 and thence in parallel, one path extending through the right-hand alternate contacts of relay 299, inner right-hand normal contacts of relay 298, left-hand normal contacts and winding of relay 294, and the other path extending through the winding of relay 296 to grounded battery. Relay 294, in operating, opens at its right-hand contacts the 55 original energizing circuit for relay 299, but relay 299 remains energized through its locking circuit. Relay 296, in operating, completes a circuit for the energization of relay 298, said circuit including grounded 60 battery, right-hand winding of relay 298 and ground at the inner left-hand contacts of relay 296. Relay 298, in operating, locks over a path including ground through the contacts of relay 218, left-hand contact and winding of relay 298 and grounded battery 70 at the left-hand contacts of relay 398. Relay 296 in operating also completes a circuit for the energization of relay 292 and the stepping magnet 303 of the switch FS, said circuit extending from ground, through the 75 lower left-hand contact of sequence switch spring 389 (1+11/4), outer right-hand contacts of relay 296, inner right-hand alternate contacts of relay 325 and thence in parallel, one path extending through the contacts and winding of stepping magnet 303 to grounded battery and the other path extending through the right-hand winding of relay 292 to grounded battery. Relay 296, in operating, also completes a circuit for the 80 energization of relay 390, said circuit extending over a path from grounded battery, through the right-hand winding of relay 390, intermediate right-hand contacts of relay 296 and upper left-hand contact of sequence switch spring 314 (1+101/4), to ground. As the line finder brush shaft is moved upwardly, brush 286 engages segment 293 causing a shunt to be placed around the winding of relay 107 whereupon 85 said relay 107 releases. When the brush 286 passes out of engagement with segment 293, relay 218 releases. 90

When the brush shaft of the line finder arrives at the terminal of the calling line, relay 214 operates over a path extending 100 from ground, through the outer right-hand contacts of relay 270, winding of relay 214, upper left-hand contact of sequence switch spring 380 (1), lower right-hand contact of 105 said spring (1), brush 207, contact 203, outer right-hand alternate contacts of relay 102 and left-hand winding of relay 105 to grounded battery. Immediately thereafter or when the brush 280 centers upon the 110 contact of the segment 283, corresponding to the calling line, the locking circuit for relay 299 is opened whereupon said relay releases and opens at its outer left-hand contacts the circuit for the updrive magnet 216 115 whereupon the upward movement of the brushes is stopped. Relay 398 then operates over a path extending from grounded battery, through the left-hand normal contacts of relay 270, left-hand alternate contacts of 120 relay 390, upper right-hand contact of sequence switch spring 381 (1+15), winding of relay 398, outer left-hand contacts of relay 296, outer right-hand normal contacts of relay 299, segment 284 and brush 281 to 125 ground. The relay 398, in operating, completes a circuit for the energization of the cut-off relay 103 of the calling line, said circuit extending over path from ground through the winding of relay 103, contact 130

- 202, brush 206, resistance 388 and left-hand alternate contacts of relay 398 to grounded battery. Relay 103, in operating, disconnects the line relay 102 from the calling line.
- 5 With sequence switch 300 in position 1, stepping magnet 303, associated with the switch FS, is energized as previously described and relay 325 is locked up to ground at a busy contact of switch FS provided
- 10 wiper 391 of the switch FS is resting on the contacts of a busy sender. So long, however, as the test wiper 391 of the switch FS encounters contacts upon which busy ground potential exists, the stepping magnet 303
- 15 will advance the wipers of the switch until an idle sender is found, when the wiper 391 will find no ground on the contacts of the idle sender and the relay 325 will thereupon become deenergized. Relay 325, in retracting its inner right-hand armature, opens the circuit previously traced for relay 292 and stepping magnet 303, and in retracting its inner left-hand armature opens the circuit for relay 394, whereupon said relays 292 and
- 20 394 release. As soon as relay 292 releases, a circuit for operating relay 365 is completed over a path extending from grounded battery, through the right and left-hand windings of relay 365, lower right and left-
- 25 hand contacts of sequence switch spring 305 (1), inner right-hand contacts of relay 398, right-hand contacts of relay 292, segment 295 and brush 282 to ground. If the sequence switch 300 remains in position 1
- 30 longer than a certain interval, an alarm signal is actuated. Relay 327 also operates over a circuit extending from grounded battery, through the right-hand winding of relay 327, upper left-hand contact of sequence switch 304 (1), upper right-hand contact of sequence switch contact 305 (1+9), lower left-hand contact of said spring (1), inner right-hand contacts of relay 398, right-hand contacts of relay 292,
- 35 segment 295 and brush 282 to ground. Sequence switch magnet 300 then operates over a path extending from grounded battery, through winding of magnet 300, lower right-hand contacts of sequence switch spring
- 40 306 (1), front contact and outer right-hand armature of relay 327, and upper right-hand contact of sequence switch spring 307 (1+5) to ground, driving sequence switch 300 from position 1 into position 2. As sequence
- 45 switch 300 moves out of position 1, the circuits for relays 327 and 365 are opened and these relays release. If, at the time relay 325 is energized, the wipers of switch FS are standing upon contacts which are connected to circuits extending to an idle office sender, relay 325 does not lock up over the circuit previously traced and the circuit previously traced through stepping magnet 303 is immediately opened at the inner right-
- 50 hand armature and front contact of relay 325 to prevent the advance of the wipers of the switch FS.
- In position 2 of sequence switch 300, relay 325 operates over a path including a grounded battery and ground at the lower right-hand contacts of spring 308 (2+13). Relay 394 then operates over an obvious circuit. With the sequence switch 300 in position 2, relay 510, associated with the selected office sender, is operated over a path extending from grounded battery, through the right-hand winding of relay 510, wiper 391 of the switch FS, outer right-hand contacts of relay 325 and lower right-hand contacts of spring 308 (2+13), to ground. Relay 510 energizes in this circuit and causes the advancement of the time measuring switch, not shown, associated with the office sender in the manner fully set forth in the patent of Stearn and Scudder, hereinbefore referred to, which time measuring switch upon leaving normal position closes the off-normal contact 511. The test contact upon which wiper 391 is now resting is marked with a busy ground potential over a circuit which may be traced from off-normal contact 511, through the left-hand winding of differential relay 510, and thence to the wiper 391, whereby the sender is marked as busy until the office sender has been restored to normal condition either following the abandonment of the call or the termination of the functioning of the office sender.
- With relays 510 and 394 energized, an impulsive circuit is now established from the conductors of the calling line through the winding of the sender pulsing relay for enabling the calling subscriber to set the registers (not shown) associated with the sender in accordance with the designation of the desired line. This circuit may be traced from ground, through the armature and front contact of relay 510, conductor 513, contact 386 and wiper 375 of the sender finder FS, inner left-hand contacts of relay 394, lower right-hand contact of sequence switch spring 313 (2+9½), conductor 117, inner left-hand contacts of relay 292, brush 205 and contact 201 of the switch LF, thence through the impulse contacts 130 of the calling subscriber's dial S, thence through the subscriber's substation circuit, contact 200 and brush 204 of the switch LF, intermediate left-hand contacts of relay 292, conductor 116, lower left-hand contact of sequence switch spring 312 (2+9½), wiper 317 and contact 385 of switch FS, thence through the winding of pulsing relay 512 to battery.
- The calling subscriber now receives a dialing tone over this circuit in the manner set forth in the aforesaid patent of Stearn et al. and then proceeds to dial the number of the desired line. Under the assumption that the subscriber desires a connection with

a subscriber's line C which line is listed in the directory as LISpenard 9532, the subscriber proceeds to dial the three letters L I S corresponding to the designation of the 5 office in which the desired line is located and then dials the four digits representing the number of the line, which number, as assumed, is 9532. The three letters which represent the district code will cause the setting 10 of code registers (not shown) associated with the office sender which, in turn, control the operation of the sender to control the setting of the district selector switch 350 and the setting of the sequence switch of 15 the district selector for determining the proper talking path through the repeating coil 336 associated with the district selector. The transmission of the impulses corresponding to the number of the desired 20 subscriber's line 9532 causes the setting of the numerical registers associated with the sender to control the sender to govern the setting of the incoming selector switch 450 and of the final selector switch 490 for extending 25 the connection to the desired line in the selected district.

Following the setting of the code registers of the sender, the sequence switch 550 associated with the office sender is driven 30 into position 2 in the manner set forth in the aforesaid patent of Stearn, et al., for establishing a fundamental circuit extending from the office sender through the winding of relay 327 of the district selector switch 35 for controlling the setting of the district 40 selector. Since at this time the sequence switch 300 of the district selector is in position 2, the fundamental circuit may be traced from grounded battery, through the left-hand winding of relay 327, the lower left-hand contact of sequence switch spring 310 (2), upper left-hand contact of said spring (2+5), outer left-hand contacts of relay 325, wiper 350 and contact 383 of 45 switch FS, upper and lower contacts of sequence switch spring 519 (2), armature and back contact of the 0' counting relay 520, the windings of the polarized relay 522, the windings of sender stepping relay 521 and thence to ground through the lower 50 left-hand and right-hand contacts of sequence switch cam 523 (2) and resistance element 524.

Relay 327 of the district selector switch 55 and stepping relay 521 of the office sender are energized in this circuit. Relay 521, upon energizing, establishes a circuit in the well-known manner for an upper counting relay of the group of counting relays associated 60 with the sender corresponding to the setting of the code registers and relay 327 closes a circuit for driving sequence switch 300 of the district selector out of position 2 and into position 3. This circuit 65 extends from grounded battery, through the

magnet winding of sequence switch 300, lower right-hand contact of sequence switch spring 306 (2), outer right-hand alternate contact of relay 327 and upper right-hand contact of sequence switch spring 307 (1+5) 70 to ground. In position 3 of sequence switch 300, a circuit is completed for relay 365 over a path including grounded battery, right-hand winding of relay 365, lower left-hand contact of sequence switch spring 316 (3+9), 75 right-hand contacts of relay 394, lower left-hand contact of sequence switch spring 333 (2+9), wiper 397 and contact 393 of switch FS, right-hand contacts of relay 537 and resistance 538 to ground. Relay 365 operates 80 in this circuit but performs no useful function at this time. With the district selector sequence switch 300 in position 3, the initial energizing circuit of relay 327 is opened at the lower left-hand contact of sequence 85 switch spring 310, but relay 327 is maintained energized over the fundamental circuit by a new circuit extending from grounded battery, through its left-hand winding, its left-hand armature and front contact and 90 thence through the lower right-hand contact of sequence switch cam 310 (1+5) and over the fundamental circuit as previously traced. A circuit is now closed for the updrive magnet 338 of the district selector, which circuit extends from grounded battery, through the winding of magnet 338, the upper right-hand contact of sequence switch spring 309 (3), the lower left-hand contact of said spring (3+18), front contact and outer 95 right-hand armature of relay 327, upper right-hand contact of sequence switch spring 307 (1+5) to ground. Magnet 338, upon energizing, presses the depending portion of the switch shaft (not shown) against the 100 constantly rotating updrive drum (not shown), thereby causing the updrive movement of the switch shaft.

As the switch shaft at the district selector switch moves upwardly and approaches its 110 first brush tripping position, brush 341 engages the first metallic portion of the commutator segment 342 and a circuit is closed as follows in shunt of the windings of the sender stepping relay 521 which may be 115 traced from grounded battery, through the left-hand winding, front contact and left-hand armature of relay 327, the lower right-hand contact of sequence switch spring 310 (1+5), upper left-hand contact of sequence 120 switch spring 311 (2 $\frac{3}{4}$ +3), conductor 343, commutator segment 342, brush 341, conductor 344, lower right-hand contact of sequence switch spring 314 (8+6), to ground. Relay 327 is maintained energized over this shunt 125 circuit but relay 521 being shunted deenergizes causing in the well-known manner the energization of the lower counting relay corresponding to the previously energized upper counting relay. As the switch shaft 130

continued its upward movement, brush 341 moves into engagement with an insulating portion of the segment 342 and the shunt around the windings of sender stepping relay 521 is removed, whereupon the sender stepping relay again energizes. In this manner, during the upward movement of the switch shaft, the stepping relay 521 of the office sender is intermittently energized and deenergized causing the successive energization of the counting relays associated with the sender. If it be assumed that the No. 2 counting relay was energized upon the initial energization of sender stepping relay 521, then, when the switch shaft of the district selector has advanced to such a position as to position the third set of brushes carried thereby in position to be tripped, the No. 0' counting relay 520 will be energized in series with the No. 0 counting relay 525 and will open the previously traced fundamental circuit at its armature and back contact. Counting relay 520 is also instrumental at this time in causing the advancement of the sender sequence switch 550 out of position 2 and into position 4. Upon leaving position 2, all counting relays which have been energized and locked up over the circuit extending from the sequence switch contact 526, become deenergized.

As soon following the opening of the fundamental circuit by the No. 0' counting relay 520 as the brush 341 engages the next insulating portion of the commutator segment 342, relay 327 becomes deenergized and closes a circuit for driving district selector sequence switch 300 out of position 3 and into position 4, and opens the circuit previously traced through the updrive magnet 338, thereby arresting the upward movement of the switch shaft. The circuit for driving sequence switch 300 in position 4 may be traced from grounded battery, through the magnet winding of sequence switch 300, lower-left-hand contact of sequence switch spring 306 (3), outer right-hand armature and back contact of relay 327 and thence to ground through the right-hand contact of sequence switch spring 307 (1+5).

With sequence switch 300 of the district selector in position 4 and the sender sequence switch 550 in position 4, the fundamental circuit previously traced is again established and relays 327 and 521 again energize. Relay 521 now establishes a circuit through one of the upper counting relays in accordance with the setting of the code registers and relay 327 establishes a circuit for driving sequence switch 300 out of position 4 and into position 5, this circuit extending from grounded battery, through the magnet winding of sequence switch 300, the lower right-hand contact of sequence switch spring 306 (4), front contact and outer right-hand armature of re-

lay 327 and right-hand contact of sequence switch spring 307 (1+5) to ground. Upon leaving position 4, sequence switch 300 opens the initial energizing circuit of relay 327 but relay 327 is now maintained 70 energized over the fundamental circuit through the lower right-hand contact of sequence switch spring 310 (1+5) and the left-hand armature and front contact and left-hand winding of relay 327. 75

Upon reaching position 5, the circuit previously traced through the winding of up-drive magnet 338 is again established through the upper right-hand contact of sequence switch spring 309 (5) and in the 80 manner previously described the switch shaft is again driven upwardly. Since at this time, however, the tripping spindle (not shown) has been rotated by the tripping magnet 346 which was energized in 85 position 4 of the sequence switch over a circuit extending from grounded battery, through the winding of tripping magnet 346 and to ground through the upper right-hand contacts of sequence switch spring 90 308, the third set of brushes is now tripped through the initial upward movement of the switch shaft and during the continued upward movement of the switch shaft the tripped set of brushes travel over the contacts of the bank with which they are associated. The remaining four sets of brushes on the switch shaft are not tripped at this time and are, therefore, functionless. 95

As the switch shaft continues its upward movement and the tripped set of brushes approaches the first set of terminals in the first group of trunks to which the set of brushes has access, the brush 347 engages the first metallic portion of commutator segment 100 348 and a circuit is closed in shunt of the windings of the sender stepping relay 521, which shunt circuit may be traced from grounded battery, through the left-hand winding, left-hand armature and front contact of relay 327, the lower right-hand contact of sequence switch spring 310 (1+5), upper right-hand contact of said spring (4 $\frac{3}{4}$ +5), conductor 349, segment 348, brush 347, conductor 344, lower right-hand contact of sequence switch spring 314 (8+6), to ground. Relay 327 is held energized over this circuit, but sender stepping relay 521 deenergizes, causing, upon its deenergization, the energization of a lower counting relay corresponding to the upper counting relay which was energized upon the initial energization of relay 521. 110

As the brush shaft continues in its upward movement, brush 347 engages an insulating portion of segment 348 and the shunt around the winding of sender stepping relay 521 is opened, whereupon relay 521 reenergizes causing the energization of the next succeeding upper counting relay. 125 130

In this manner during the continued advancement of the switch shaft, the stepping relay 521 of the sender is intermittently energized and deenergized to energize and lock up successive lower and upper counting relays. If it be assumed that the subscriber has set the code registers in such a manner as to cause the No. 0 lower counting relay 525 to become energized upon the initial energization of relay 521, then upon the first deenergization of relay 521, the No. 0' counting relay 520 will become energized in series with relay 525, thereby opening the fundamental circuit and causing the advance of the sender sequence switch 550 from position 4 into position 6. At this time the selected set of brushes of the district selector switch will be positioned upon the lowermost set of terminals of the first group of its associated bank. Upon the advance of sequence switch 550 out of position 4, the locking circuit of counting relays 520 and 525 is opened at sequence switch spring 526.

As soon following the opening of the fundamental circuit by the No. 0' counting relay 520 as the brush 347 engages the next insulating portion of commutator 348, relay 327 becomes deenergized, opening at the front contact of its inner right-hand armature, the previously traced circuit of the up-drive magnet 338 to arrest the upward movement of the switch shaft, and closing at the back contact of its outer right-hand armature the previously traced circuit for advancing sequence switch 300 out of position 5 and into position 6.

At the time sequence switch 300 moved into position 5, a circuit was established for advancing the steering switch RS from position 1 to position 2. This circuit may be traced from grounded battery, through wiper 247, contact 227, winding of stepping magnet 230, wiper 231, contact 232, conductor 233 and thence to ground through the upper left-hand contact of sequence switch spring 389. Stepping magnet 230 energizes in this circuit and is held energized until sequence switch 300 leaves position 6 $\frac{1}{4}$ when magnet 230 deenergizes to advance the wipers of switch RS to the second position contacts.

With sequence switch 300 in position 6, a circuit is established for relay 327 which may be traced from grounded battery through its right-hand winding, left-hand contact of sequence switch spring 304 (6+6 $\frac{1}{2}$), upper right-hand contact of sequence switch spring 305 (1+9), lower left-hand contact of said spring (6+7), inner right-hand contacts of relay 398, right-hand contacts of relay 292, segment 295 and brush 282 to ground. Relay 327, upon energizing, closes a circuit for driving sequence switch 300 out of position 6 and into posi-

tion 7. This circuit may be traced from grounded battery, through the magnet winding of sequence switch 300, lower right-hand contact of sequence switch spring 306 (6), outer right-hand contacts of relay 327, upper left-hand contacts of sequence switch spring 307 (6+7), right-hand alternate contacts of relay 390 and lower left-hand contact of sequence switch spring 314 (1 $\frac{1}{2}$ +18 $\frac{1}{4}$) to ground. 75

As soon as sequence switch 300 leaves position 6 $\frac{1}{2}$, the initial energizing circuit of relay 327 is opened at sequence switch spring 304, but if the first trunk in the group of trunks upon which the brushes 351, 352 and 353 are now standing is busy, a ground potential exists on the test terminal 354 and relay 327 is maintained energized over a circuit extending from grounded battery, through its left-hand winding, armature and front contact, lower left-hand contact of sequence switch spring 315 (6 $\frac{1}{2}$ +8), lower right-hand contact of said spring (1+14), inner right-hand contacts of relay 327, right-hand contacts of sequence switch spring 382 (6+7), brush 350 and terminal 354, and when sequence switch 300 reaches position 7, a circuit is established for the updrive magnet 338. The circuit of updrive magnet 338 may be traced from grounded battery, through the winding of this magnet, upper right-hand contact of switch spring 309 (7), lower left-hand contacts of said spring (3+18), outer right-hand alternate contacts of relay 327, and upper right-hand contact of sequence switch spring 307 to ground. The updrive magnet 338, upon energizing, drives the brushes upwardly in search of an idle trunk in the selected group. So long as the test brush 350 encounters the terminals of busy trunks, relay 327 remains locked. When, however, an idle trunk is encountered which it will be assumed is the trunk terminating in terminals 355, 356 and 357, the locking circuit of relay 327 is opened as no ground potential exists on the test terminal 357 and relay 327 deenergizes as soon as the brushes have been properly centered on the bank terminals 351, 352 and 353. Until the brushes are centered, relay 327 is maintained locked over a circuit extending through its right-hand winding, the upper right-hand contact of sequence switch spring 304 (7), segment 359, brush 360, upper left-hand contact of sequence switch spring 309 (7), lower left-hand contact of said spring (3+18), outer right-hand alternate contacts of relay 327, and upper right-hand contacts of sequence switch spring 307 (6 $\frac{1}{2}$ +9) to ground. Relay 327, upon deenergizing, opens the circuit of updrive magnet 338, thereby arresting the brushes 351, 352 and 353 upon the terminals 355, 356 and 357 of the trunk line extending to the district of the exchange in which the desired 130

line terminates. Relay 327, upon deenergizing, also establishes the previously traced circuit for driving the sequence switch 300 out of position 7 and into position 8.

5 As soon as sequence switch 300 reaches position $7\frac{3}{4}$, a busy ground potential is placed on the multiples of test terminal 357, over a circuit which may be traced from ground, through the upper left-hand contact of sequence switch spring 315, ($7\frac{3}{4} + 13\frac{1}{2}$), upper right-hand contact of said spring (6+15), segment 362, brush 363, brush 350 and thence to the multiples of terminal 357.

10 15 With sequence switch 300 in position 8, relay 365 is operated over the path previously traced, including ground at resistance 538, and grounded battery at right-hand winding of relay 365. In position 8 of sequence switch 300, relay 327 is again operated over a circuit extending from grounded battery, through the right-hand winding of relay 327, left contact of sequence switch spring 304, upper left-hand contact of sequence 20 switch spring 305 (1+9), upper left-hand contact of said spring (8+16 $\frac{1}{4}$), and outer right-hand contacts of relay 365 to ground. Relay 327, upon energizing, closes a circuit through its outer right-hand armature and front contact for driving sequence 25 switch 300 out of position 8 and into position 9. This circuit extends from grounded battery, through the magnet winding of sequence switch 300, lower right-hand contact 30 of sequence switch spring 306, outer right-hand contacts of relay 327 and upper right-hand contact of sequence switch spring 307 to ground.

35 In position 9 of sequence switch 300, relay 327 is held energized over the circuit just traced until selection beyond the district selector 350 has been completed. In position 9 of sequence switch 350, the fundamental circuit is extended from the office 40 sender through contacts of sequence switch springs 318 and 319 of the district selector to the line relay 421 of the incoming selector switch 450. The fundamental circuit may be traced from grounded battery, through the left-hand winding of relay 421, lower contact of sequence switch spring 402 (1+10), upper contact of said spring (1), resistance 424, lower contact of spring 403 (1+10), conductor 419, terminal 355, brush 45 50 55 60 65 351, upper right-hand contact of spring 318 (9+14), lower left-hand contact of said spring (9), outer left-hand contacts of relay 325, wiper 350 and contact 383, upper and lower contacts of spring 519 (6), contacts of the counting relay 520, windings of relays 522 and 521, lower and upper contacts of spring 523 (6), wiper 339 and its associated contact, lower right-hand contact of spring 319 (9), upper right-hand contact of said spring (9+14), brush 352, terminal

356, conductor 420, upper contact of spring 404 (1+10), resistance 425 and lower contact of spring 405 to ground. Relays 521 and 421 energize in this circuit. In a manner fully described in the Taggart, et al. 70 patent hereinbefore mentioned, the incoming selector switch is then set after which the final selector switch is set in its tens and units selection movements. During the units selection movement of the final selector switch, steering switch RS is in position 75 2, sequence switch 300 is in position 9, sequence switch 400 will be in position 8 and relay 421 of the incoming selector switch will be energized in the manner described 80 in the Taggart et al. patent.

Following the units selection movement of the final selector switch and during the testing operation of the switch, the circuit of relay 421 is opened causing the deenergization of this relay. Relay 421, upon deenergizing, closes a circuit for driving sequence switch 400 out of position 8 and into position 9. This circuit may be traced from grounded battery, through the winding of sequence switch magnet 400, upper left-hand contact of sequence switch spring 406 (8), and thence to ground at the inner left-hand armature and back contact of relay 421. With sequence switch 400 in position 9, relay 421 is again connected into the fundamental circuit extending through the windings of the sender stepping relay 521 and the windings of overflow relay 522, but since at this time the winding of relay 100 105 110 115 120 125 130 421 is connected to the ring conductor of the fundamental circuit rather than to the tip conductor as described in the Taggart et al. application, current flowing in the fundamental circuit now flows in a direction reverse to that direction in which it originally flowed. The circuit of relay 421 may be traced from grounded battery, through the left-hand winding of relay 421, lower contacts of sequence switch spring 415 (9), resistance element 425, upper contact of sequence switch spring 404 (1+10), thence over the fundamental circuit as previously traced and returning through the lower contact of sequence switch spring 403 (1+10), resistance element 424, contacts of sequence switch spring 408 (9), and thence to ground through the upper contacts of sequence switch spring 412.

The current now flowing over the fundamental circuit is in such a direction as to energize both the sender stepping relay 521 and the overflow relay 522. Overflow relay 522, upon energizing, establishes a circuit for the advance relay 537, which, at its armature and back contact, opens the previously traced circuit through the winding of call charging relay 365. Relay 365 thereupon deenergizes opening the circuit of relay 327, which thereupon deenergizes

and establishes the previously traced circuit for driving sequence switch 300 of the district selector out of position 9 and into position 10. With sequence switch 300 in position 10, a circuit is now established 5 from grounded battery, through the left-hand winding of relay 327 of the district selector switch, lower left-hand contact of sequence switch spring 310 (10), upper left-hand contact of said spring (10+18), front contact and outer left-hand armature of relay 325, wiper 350 and contact 383 of the sender finder FS, upper and lower contacts of sequence switch spring 519 (16), armature and back contact of the No. 0' counting relay 520, winding of overflow relay 522 and sender stepping relay 521, and thence to ground through the lower contacts of sequence switch spring 523 (16). Relays 20 327 and 521 energize in this circuit, the relay 521 establishing a circuit for the lower counting relay for controlling the subsequent movement of the sequence switch 300 of the district selector for controlling talking selection. In this case it will be assumed that the No. 0 counting relay has 25 been prepared for operation through the setting of code registers by the calling subscriber.

Upon the movement of sequence switch 30 out of position 9½, the impulsing circuit over which the calling subscriber set the registers of the office sender is opened at contacts of sequence switch springs 312 and 313, and the talking conductors of the district selector trunk are now connected over contacts of these springs to wipers 242 and 243 of the steering switch RS. Sequence switch 300, upon reaching position 9¾, establishes a circuit for advancing the steering switch RS from position 2 to position 3. This circuit may be traced from grounded battery through the back contact and armature and winding of stepping magnet 230, 40 wiper 231, the position 2 contact upon which it is now standing, conductor 233, and thence to ground through the upper left-hand contact of sequence switch spring 389 (9¾+10½). When the steering switch reaches 45 position 3, a circuit is established for relay 224 which may be traced from ground, through the left-hand winding of this relay, third contact associated with wiper 247, wiper 247 to grounded battery. Relay 224, 50 upon energizing, establishes a circuit for the test relay 249 which may be traced from grounded battery, through the winding of this relay, right-hand non-inductive winding, front contact and right-hand armature 55 of relay 224, third contact associated with the wiper 266, wiper 266, conductor 248, lower left-hand contact of sequence switch spring 380 (10), upper right-hand contact of said spring (2+18) to ground. The resistance of 60 the right-hand winding of relay 244 is so se-

lected that if relay 249 energizes in series therewith, relay 249 will consequently energize over the line resistance of any calling subscriber's line to which it may be later connected in testing for a discriminatory condition upon such subscriber's line. If relay 249 energizes, a circuit is immediately closed for energizing relay 252, which circuit may be traced from grounded battery, 70 through the right-hand winding of relay 252, front contact and outer left-hand armature of relay 224, and thence to ground at the armature and front contact of relay 249. Relay 252, upon energizing, establishes a circuit for advancing the steering switch out 75 of position 3 and into position 4, this circuit extending from grounded battery, through the back contact, armature and winding of stepping magnet 230, wiper 231, the third position contact upon which it is resting, and thence to ground at the outer right-hand armature and front contact of relay 252. Relay 252 performs no other useful function at this time. As soon as the steering switch leaves position 3, the circuit of relay 249 is opened and relays 249 80 and 252 release.

If the test relay 249 fails to energize when connected to the right-hand winding of relay 224 upon the routine test to determine the sensitiveness of relay 249, then the steering switch remains in position 3 and relay 224 is maintained energized for a sufficient time to connect ground through its outer left-hand armature and front contact to the circuit extending to the selector time alarm for causing the selector time alarm to operate.

When the steering switch reached position 3, a circuit was established for the answering supervisory relay 370, which may be traced from grounded battery, through the lower left-hand winding of repeating coil 336, winding of relay 370, conductor 371, wiper 243 of the steering switch and its third position contact, and thence to ground through the right-hand non-inductive winding of relay 222. This circuit is maintained through position 9 of the steering switch. Relay 370, upon energizing, establishes a holding circuit for the slow-to-release relay 390 extending from grounded battery through the right-hand winding of relay 390, front contact and armature of relay 370, right-hand armature and alternate contact of relay 390, and thence to ground through the lower left-hand contact of sequence switch spring 314 (1½+18½). The above traced locking circuit holds relay 390 operated after its initial energizing circuit through the upper left-hand contact of sequence switch spring 314 (1+10½) is opened as the sequence switch 300 is advanced beyond position 10.

When relay 252 deenergizes, a circuit for

moving the steering switch from position 4 to position 5 is completed as follows: grounded battery, back contact, armature and winding of magnet 230, wiper 231 and 5 the fourth position contact with which it is associated, back contact and outer right-hand armature of relay 252 to ground.

When the wipers of the steering switch reach position 5, a circuit is established for 10 the stepping magnet 230 extending from grounded battery, through the fifth position contact of wiper 247, wiper 247, the winding of magnet 230, wiper 231 and the fifth position contact upon which it is resting, and to 15 ground at the contact controlled by interrupter cam 254 for advancing the steering switch from position 5 to position 6, as soon as the cam 254 makes and interrupts its contact. Upon reaching position 6, the circuit 20 of magnet 230 is again established through the contact of cam 254 and the switch continues to advance under the control of cam 254 into position 8. Upon reaching position 25 8, a circuit is established for magnet 230 extending from grounded battery, through the eighth position contact of the switch wiper 247, magnet 230, wiper 231 and the eighth position contact upon which it is resting, conductor 233, and thence to ground through 30 the upper left-hand contact of sequence switch spring 389 ($9\frac{3}{4} + 10\frac{1}{2}$). The magnet is held energized over this circuit and does not advance the wipers of the steering switch from position 8 until sequence switch 300 35 leaves position $10\frac{1}{2}$.

During the time that the steering switch is advancing through positions 3 to 6, inclusive, the tip conductor of the subscriber's line is connected to grounded battery for the 40 purpose of removing any charge that may have accumulated on the line and which might later erroneously affect the testing circuit established through the testing relay 249. This circuit may be traced from conductor 116 through the lower right-hand contact of sequence switch spring 312 ($9\frac{3}{4} + 13\frac{1}{2}$), conductor 372, wiper 242, contacts 3 to 6 over which this wiper passes, to 45 grounded battery. When the steering switch reaches position 7, the winding of the test relay 249 is connected to the tip conductor of the subscriber's line, and if, as in the case assumed, the subscriber 50 at substation A of the calling line has initiated the call, the relay 249 will 55 energize over a circuit which may be traced from grounded battery, through the winding of relay 249, the seventh position contact associated with the wiper 242, wiper 242, conductor 372, lower right-hand contact of sequence switch spring 312 ($9\frac{3}{4} + 13\frac{1}{2}$), trunk conductor 116, back contact and intermediate left-hand armature of relay 292, brush 204, contact 200, primary winding of the 60 substation repeating coil 128, switchhook 65

contact 129 and thence to ground through the subscriber's call bell 131. Relay 249 energizes in this circuit and as relay 224 is at this time deenergized, establishes a circuit for the switching relay 222 which may be traced 70 from grounded battery, through the left-hand winding of relay 222, conductor 256, front contact and outer left-hand armature of relay 394, back contact and outer left-hand armature of relay 224, and thence to 75 ground through the armature and front contact of relay 249. Relay 222 energizes in this circuit and establishes a locking circuit for itself extending from grounded battery, through its left-hand winding, front contact 80 and left-hand armature, and lower left-hand contact of sequence switch spring 314 ($1\frac{1}{2} + 18\frac{1}{4}$), to ground. The previously traced circuit for test relay 249 is maintained through wiper 242 of the steering 85 switch until the steering switch leaves position 8.

With the wipers of the steering switch standing on their eighth position contacts, a circuit is established for advancing the sequence switch 300 of the district selector out 90 of position 10. This circuit may be traced from grounded battery through the magnet winding of sequence switch 300, lower right-hand contact of sequence switch spring 306 95 ($10 + 13$), front contact and outer right-hand armature of relay 327, (the relay 327 being maintained energized at this time over the fundamental circuit extending through the sender stepping relay 521), eighth position 100 contact upon which wiper 266 of the steering switch is now resting, wiper 266, conductor 248, lower left-hand contact of sequence switch spring 380 (10), and upper right-hand contact of said sequence switch spring (2+18) to ground. Upon reaching position 11, the circuit for advancing the sequence switch is maintained over the right-hand contacts of sequence switch spring 307 105 and the switch advances through the successive talking selection positions. Relay 327 is maintained energized in position 11 of sequence switch 300 by a circuit from grounded battery, through its left-hand winding, armature and front contact, lower right contact of spring 310, (10+17), upper left contact of 310 (10+13) outer left-hand contact 110 of relay 325 and thence to ground over the fundamental circuit.

As soon as the sequence switch 300 leaves 120 position $10\frac{1}{2}$, the previously traced energizing circuit of stepping magnet 230 of the steering switch is opened and the magnet 230 advances the wipers of the steering switch out of position 8 and into position 9. 125 In position 9, a circuit is established from grounded battery through the armature, contacts and winding of stepping magnet 230, wiper 231, to ground on the ninth position contact upon which it is resting for ad- 130

vancing the wipers of the steering switch over the ninth position into position 10. In position 10, the trunk conductors 116 and 117 are connected through the wipers 242 and 243 of the steering switch to conductors 372 and 371, and the answering supervisory relay 370 is now maintained energized over the calling subscriber's loop.

As the district selector 300 passes through position 10 $\frac{1}{2}$, a shunt circuit is established in shunt of the windings of the sender stepping relay 521, which may be traced from grounded battery, through the left-hand winding, left-hand armature and front contact of relay 327, lower left-hand contact of sequence switch spring 315 and to ground at the upper left-hand contact of sequence switch spring 315 ($7\frac{3}{4}+13\frac{1}{2}$). Relay 327 is maintained in this circuit but the sender stepping relay 521 becomes deenergized and in the well-known manner causes the energization of the upper counting relay corresponding to the lower counting relay which was energized upon the initial energization of sender stepping relay 521 in the talking selection position (16) of the sender sequence switch 550. Since, in the case assumed, the No. 0 counting relay 525 was thus initially energized, the No. 0' counting relay 520 now energizes and opens the fundamental circuit at its armature and front contact.

The energization of the No. 0' counting relay 520 causes relay 327 to become deenergized since its locking circuit is now open. Relay 327, upon deenergizing, opens the driving circuit of sequence switch 300 and the sequence switch is arrested upon reaching position 11.

After sequence switch 300 leaves position 10, relay 325 is maintained energized to maintain the fundamental circuit closed through the winding of relay 327 until it is interrupted by the No. 0' counting relay of the office sender over a circuit which may be traced from grounded battery through the right-hand winding of relay 325, upper right-hand contact of sequence switch spring 316 (10+13), front contact and right-hand armature of relay 394, upper right-hand contact of sequence switch spring 333 (10+15), front contact and inner right-hand armature of relay 327, lower right-hand contact of sequence switch contact 315 (1+14), upper left-hand contact of sequence switch spring 315 ($7\frac{3}{4}+13\frac{1}{2}$) to ground. As soon as the talking selection is completed and relay 327 deenergizes as above described, this holding circuit for relay 325 is opened and relay 325 deenergizes, thereby opening the circuits controlled thereby. At the office sender upon the opening of the fundamental circuit the sequence switch of the office sender is driven into normal position and

the circuits of the sender are restored to normal in the well-known manner.

Upon the setting of the sequence switch 300 of the district selector switch into its talking selection position, the incoming selector switch functions to apply ringing current and when the called subscriber answers relay 421 deenergizes whereupon the ringing current is disconnected from the called line and the sequence switch 400 is driven from position 14 to 16, all as described in the aforementioned patent to Taggart and Scudder.

As soon as sequence switch 400 reaches position 14, a direct current path is established through the right-hand winding of repeating coil 458, and thence over the called subscriber's line for supplying the called subscriber's line with talking current. This path may be traced from grounded battery through the lower right-hand winding of repeating coil 458, winding of supervisory relay 459, contact of sequence switch spring 414 (14+16), brush 448 and terminal 449 of the incoming selector switch, brush 480, and terminal 482 of the final selector switch, thence through the called subscriber's substation loop, terminal 486 and brush 484 of the final selector switch, terminal 447 and brush 446 of the incoming selector switch, contact of sequence switch spring 413 (13 $\frac{3}{4}+16$), and thence to ground through the upper right-hand winding of repeating coil 458. Supervisory relay 459 energizes in this circuit and connects the terminals of the central station battery between the left-hand windings of repeating coil 458 in such a manner as to cause current to flow over the trunk line incoming through the selector switch and the district selector switch in such a manner as to energize the polarized call charging relay 374 at the district selector switch to close its alternate contact. This circuit may be traced from grounded battery over conductor 460, through the upper contact of sequence switch spring 405 (11+16), conductor 426, resistance element 425, upper contacts of sequence switch spring 415 (11 to 16), lower left-hand winding of repeating coil 458, lower contact of sequence switch spring 404 (11+16), trunk conductor 420, contact 356 and brush 352 of the district selector switch, upper right-hand contact of sequence switch spring 319 (9+14), lower left-hand contact of sequence switch spring 319 (11+13 $\frac{1}{4}$), lower right-hand winding of repeating coil 336, upper left-hand contact of sequence switch spring 396 (10+11 $\frac{1}{2}$), winding of polarized relay 374, upper right-hand contact of sequence switch spring 395 (10+13 $\frac{1}{4}$), upper left-hand contact of sequence switch spring 395 (10+11 $\frac{1}{2}$), upper right-hand winding of repeating coil 336, upper left-

hand contact of sequence switch spring 318 (11+13 $\frac{1}{4}$), upper right-hand contact of sequence switch spring 318 (9+14), brush 351 and contact 355 of the district selector switch, trunk conductor 419, upper contact of sequence switch spring 403 (11+16), upper left-hand winding of repeating coil 458, resistance 424, and thence through the armature and contact of supervisory relay 459 to ground.

The calling and called subscribers are now connected over a talking circuit with each other, shown on the drawing by heavy lines, the calling subscriber receiving current over the circuit previously traced through the left-hand winding of repeating coil 336, and the called subscriber receiving current over the repeating coil 458.

Upon the energization of polarized relay 374 with the sequence switch 300 of the district selector in talking position 11, a circuit is established for relay 252 as soon as interrupter cam 259 rotates to such a position as to close contacts 260. This circuit may be traced from grounded battery, through the left-hand winding of relay 252, contacts 260, conductor 261, upper and lower right-hand contacts of sequence switch spring 324 (11+12), alternate contacts of polarized relay 374 and upper right-hand contact of sequence switch spring 314 (11+13 $\frac{1}{2}$), to ground. Relay 252, upon energizing, locks up through its left-hand winding and outer left-hand contacts to conductor 261, and at its inner left-hand armature prepares a circuit for the call charging relay 365 which is closed upon the advance of the interrupter cam 259 to a position in which its contacts 260 are opened and its contacts 262 are closed. This circuit may be traced from grounded battery, through the right and left-hand windings of relay 365, contacts 262, front contact and inner left-hand armature of relay 252, outer left-hand armature and front contact of relay 252, and thence to ground on conductor 261. Relay 365, upon energizing in this circuit, closes a locking circuit for itself extending through its windings, lower right-hand and upper left-hand contacts of sequence switch cam 305, and to ground at the outer right-hand contacts of relay 365. At its innermost right-hand armature, relay 365 prepares a circuit for charging a call on the calling party's message register as soon as the calling party restores the receiver to the switchhook to release the established connection.

Following the termination of the conversation, both the calling and called subscribers restore their respective receivers to their switchhooks and the circuit previously traced through the answering supervisory relay 370 is opened at the switchhook contacts at the calling subscriber's station. This relay upon deenergizing opens the lock-

ing circuit of slow to release relay 390, which, after an interval, closes a circuit for driving sequence switch 300 out of position 11 into position 16. This circuit may be traced from grounded battery, through the winding of sequence switch magnet 300, lower left-hand and upper left-hand contacts of sequence switch spring 323 (11+15), right-hand normal contacts of relay 390 and lower left-hand contacts of sequence switch spring 314 (11 $\frac{1}{2}$ +18 $\frac{1}{4}$) to ground. Upon the deenergization of relay 390, the circuit previously traced extending through the windings of sleeve relay 398 is opened at the left-hand alternate contacts of relay 390 and relay 398 thereupon releases.

When sequence switch 300 reaches position 13, a circuit is established to the stepping magnet 230 of the steering switch RS for advancing the wipers of the steering switch from position 10 into position 11, which circuit may be traced from grounded battery through the 10th position contact, upon which wiper 247 is resting, wiper 247, winding of stepping magnet 230, wiper 231 and the 10th position contact upon which this wiper is standing, conductor 233, and thence to ground at the upper left-hand contact of sequence switch spring 389 (13+13 $\frac{1}{2}$). This circuit is maintained until the sequence switch leaves position 13 $\frac{1}{2}$ when stepping magnet 230 deenergizes, advancing the wipers to position 11. In position 11, the talking circuit extending through wipers 242 and 243 is still maintained in order that a tone signal may be transmitted to the calling subscriber in case the district selector switch had failed to find an idle trunk extending to an incoming selector switch and had therefore moved to its overflow position. This operation of the district selector will be described hereinafter. When sequence switch 300 passes into position 14 $\frac{1}{4}$, the previously traced circuit for magnet 230 is again established and when the sequence switch leaves position 15 $\frac{1}{4}$ the stepping magnet 230 advances the wipers of the steering switch from position 11 to 12, where, under the control of the contact of the interrupter 254, stepping magnet advances the wipers of the steering switch to position 16.

While the wipers of the steering switch are passing over positions 12 and 13, the tip conductor of the calling subscriber's line is connected over the wiper 242, to grounded battery to discharge the subscriber's line and, when passing over positions 14 to 16, the testing relay 249 is again connected to the tip conductor of the calling line to test for an unstandard condition of the line. If the calling line is in a standard condition, no ground is connected at this time, since the calling subscriber has restored his receiver to the switchhook and has thereby

disconnected the ground connection through the call bell 131, as previously described. If, however, the line is in an unstandard condition and either the ring or tip conductors are permanently connected to ground through a stray ground connection, the test relay 249 will become energized at this time. In order that the test may be made both on the tip and ring conductors, 5 they are bridged together at this time over a circuit extending from conductor 116 through the lower right-hand contact of sequence switch spring 312 (14 $\frac{3}{4}$ +17), left-hand contacts of charging relay 365 and 10 thence to conductor 117 through the lower right-hand contact of sequence switch spring 313 (16).

If the test relay 249 operates on this second test, a holding circuit is established for 15 relay 252 for maintaining this relay energized when the steering switch reaches position 16. Relay 252 is operated over a local circuit while the steering switch was passing from position 9 to 15 which may be traced from grounded battery, through its right-hand winding, contacts 9 to 15 over which the wiper 266 passes, wiper 266, conductor 248 and thence to ground through the lower 20 left-hand contact of sequence switch spring 380 (15 to 18) and upper right-hand contact of said spring (2+18) to ground. The holding circuit for relay 252 may be traced from grounded battery, through its right-hand winding, outer left-hand armature and 25 front contact of relay 224 and thence to ground at the armature and front contact of relay 249. With relay 252 operated when the steering switch RS reaches position 16, the steering switch is arrested in position 16 30 and the circuit is established to the selector time alarm extending from ground on conductor 248, wiper 266, the 16th position contact upon which the wiper rests and over conductor 264 to the selector time alarm.

The operation of the selector time alarm 35 warns the switchboard attendant that an unstandard condition obtains on a connection that has been established through the particular district selector switch with which the time alarm is associated. The operation 40 of relay 249 at this time prevents the registration of the call upon the message register of either of the parties on the calling line, and therefore prevents the registration of a 45 call on the register of the party A when the party A may not have been the calling party.

If the test relay 249 does not operate on 50 the second test, relay 252 will not be held energized when the steering switch reaches position 16 and the steering switch will, therefore, be advanced out of position 16 by a circuit extending from grounded battery, 55 through the back contact, armature and winding of stepping magnet 230, wiper 231, 60 the 16th position contact upon which it is resting and to ground at the outer right-hand, normal contacts of relay 252. When the wipers of the steering switch have reached position 17 they are advanced into 70 position 20 through the operation of interrupter cam 254 in the manner previously described.

As the steering switch RS passes through 75 positions 17, 18 and 19 and with relay 222 operated as previously described, relay 296 will be shunted down by a path including grounded battery, resistance 250, inner right-hand contacts of relay 222, 17th, 18th and 19th position contacts of wiper 266, 80 wiper 266, conductor 284, lower left-hand contact of sequence switch spring 380 (15+18) and ground at the upper right-hand contacts of said spring (2+18), causing the release of relay 398 and the cut-off relay 103, associated with calling subscriber's line. The circuit for operating the message register associated with the calling line is then completed over a path extending from ground, 85 through the message register magnet 123, back contact and outer right-hand armature of relay 103, back contact and outer right-hand armature of relay 102, contact 203 and brush 207, resistance 297, contacts of relay 279, outer right-hand alternate contacts of 90 relay 222, inner right-hand normal contact of relay 252, lower left-hand contact of sequence switch spring 381 (16), upper left-hand contact of said spring (11+16), and inner right-hand contacts of charging relay 365 to grounded battery. The message register now operates in a manner well known in the art and registers a call against the calling party A. 95

If station B had been the calling station, 100 relay 249 and consequently relay 222 would not have energized in position 7 of the steering switch RS. Relay 296 will not be shunted down in positions 17, 18 and 19 of the steering switch and relay 398 will remain 105 operated. The circuit for maintaining relay 398 operated includes grounded battery at the inner right-hand contacts of relay 365, upper left-hand contacts of sequence switch spring 381 (11+16), winding of relay 398, outer left-hand contacts of relay 296, right-hand normal contacts of relay 299, segment 284 and ground at brush 281. Since relay 398 is held at this time, relay 103 remains 110 operated. The circuit for operating the message register may be traced from ground, through the message register 144, front contact and right-hand armature of relay 103, outer armature and back contact of relay 102, contact 203, brush 207, resistance 297, 115 outer right-hand normal contacts of relay 222, inner right-hand contacts of relay 252, lower left-hand contacts of sequence switch spring 381 (16), upper left-hand contacts of 120 said spring and inner right-hand contacts 125 130

of relay 365 to grounded battery. The message register then operates in a manner well known in the art and registers a call against the station B.

- 5 During the advancement of the wipers of the steering switch from position 16 to 20, this battery is supplied for operating the message register, the movement of the steering switch leaving sufficient time for the operation of the registers. When the steering switch reaches position 20, a circuit is established for advancing sequence switch 300 out of position 16 into position 17, said circuit extending over a path from grounded battery, through the winding of sequence switch magnet 300, lower left-hand contact of sequence switch spring 306 (16), back contact and outer right-hand armature of relay 327, 20th position contact associated with wiper 266, wiper 266, lower left-hand contact of sequence switch spring 380 (15+18), and upper right-hand contact of said spring (2+18) to ground. In position 17, the sequence switch 300 is advanced to position 18 under control of spring 301. With sequence switch 300 in position 18, a circuit is established for advancing the steering switch into position 21, which circuit may be traced from grounded battery, through the back contact, armature and winding of the stepping magnet 230, wiper 231, the twentieth position contact with which it is associated, lower right-hand contact of sequence switch 323 (18), upper left-hand contact of said spring (18), right-hand normal contacts of relay 390, thence to ground to the lower left-hand contact of sequence switch spring 314 (1½+18½). With sequence switch 300 in position 18 and the steering switch in position 21, a circuit is now established for the downdrive magnet 376 of the district selector switch, which may be traced from grounded battery, through the winding of magnet 376, conductor 377, the 21st position contact with which wiper 266 is in engagement, wiper 266, conductor 248, lower left-hand contact of sequence switch spring 380 (15+18) and upper right-hand contact of said spring (2+18) to ground. The down-drive magnet 376 upon being energized, presses the depending portion of the switch shaft, not shown, against the constantly rotating down-drive drum, not shown, whereby the switch shaft is driven downwardly into the normal position in a manner well known. When the switch shaft reaches its normal position, the brush 360 engages the normal segment 379 of the switch commutator and a circuit is established for advancing the steering switch into position 22. This circuit may be traced from battery through the armature, contact and winding of magnet 230, wiper 231, 21st position contact with which the wiper 231 is in engagement, 21st
- position contact with which the wiper 291 is in engagement, normal segment 379, brush 360, conductor 344, and thence to ground through the lower right-hand contact of sequence switch 314 (8+6). In position 22, 70 an obvious circuit is completed through wiper 231 for driving the steering switch into normal position. With the steering switch in normal position, a circuit is now established for driving sequence switch 300 75 into normal position which may be traced from grounded battery, through the magnet winding of sequence switch 300, upper right-hand contact of sequence switch spring 306 (4+18), the normal or No. 1 contact with 80 which wiper 291 of the steering switch is in engagement, wiper 291, normal segment 379, brush 360, conductor 344 and thence to ground through the lower right-hand contact of sequence switch spring 314 (8+6). 85
- With sequence switch 300 in position 18 and with relay 390 deenergized, a circuit for relay 270 was completed over a path extending from grounded battery, through the left-hand normal contacts of relay 270, 90 through the left-hand normal contacts of relay 390, lower and upper left-hand contacts of sequence switch 324 (17+18), left-hand winding of relay 270, segment 284 of the switch LF and brush 281 to ground. Relay 95 270, in operating, starts the down-drive of the line finder switch LF. Relay 270, in attracting its outer right-hand armature completes an obvious circuit through the left-hand winding of relay 292 causing the energization of said relay 292. Relay 292, in operating, holds the tip and ring talking conductors 116 and 117 open during the down-drive. When the commutator brushes 280 to 282 inclusive of the switch LF are returned to normal position, the circuits for relays 270 and 296 are opened causing the release of said relays. 105
- As the sequence switch 300 leaves position 18½, the circuit for relay 298 is opened 110 at the lower left-hand contacts of sequence switch spring 314 (1½+18½) and if relay 296 is released at the end of the down-drive movement of the line finder, relay 298 will become deenergized. 115
- As soon as sequence switch 300 of the district selector switch leaves position 14, the circuit for the relay 421 associated with the incoming selector switch is opened, whereupon said relay 421 releases and causes 120 the restoration of the incoming selector to normal, after which the final selector is restored to normal in the manner described in the aforementioned Taggart et al. patent. 125
- If during the hunting movement of the district selector switch with sequence switch 300 in position 7, the switch fails to find an idle trunk in the selected group, the shunt circuit previously traced through the winding of relay 327 is opened and relay 327 be- 130

comes deenergized, opening the circuit of up-drive magnet 338 and establishes the previously traced circuit for driving the sequence switch 300 out of position 7 and into position 8. In position 8, relay 327 becomes energized over a local circuit extending from grounded battery, through its right-hand winding, upper left-hand contact sequence switch spring 304 (8+9), upper 10 right-hand contact of sequence switch spring 305 (1+9), upper left-hand contact of said spring (8+16 $\frac{1}{4}$), and the outer right-hand contacts of relay 365 to ground, and closes at its outer right-hand armature 15 and front contact, a circuit for driving sequence switch 300 out of position 8 and into position 9. In position 9, relay 327 is maintained energized over the previously traced circuit. A circuit is now established for 20 driving sequence switch 300 out of position 9 to position 10 which circuit may be traced from grounded battery, through sequence switch magnet 300, lower left-hand sequence switch spring 311 (9), upper left-hand contact of spring 311 (9+13), conductor 343, commutator segment 342, brush 341, conductor 344, and thence to ground through the lower right-hand contact of sequence 25 switch spring 314 (8+6). When sequence switch 300 reaches position 10, a circuit is established for relay 327 which is traced from grounded battery, through the left-hand winding of relay 327, lower left-hand contact of sequence switch spring 310 (10), 30 upper left-hand contact of sequence switch spring 311 (9+13), conductor 343, commutator segment 342, brush 341, conductor 344 and thence to ground through the lower right-hand contacts of sequence switch 35 40 spring 314 (8+6). The steering switch has at this time positioned its wipers on the No. 8 contacts of its banks in the manner previously described and a circuit is established through the outer right-hand armature and front contact of relay 327 for driving sequence switch 300 out of position 10. When the sequence switch leaves position 45 50 55 60 65 70 75 80 85 90 95 100 105 110 115 120 125 130 135 140 145 150 155 160 165 170 175 180 185 190 195 200 205 210 215 220 225 230 235 240 245 250 of sequence switch spring 306 (14) back contact and outer right-hand armature of relay 327 and thence to ground through the upper right-hand contact of sequence switch spring 307 (11+15). 70

As previously described, when sequence switch 300 passes out of position 10, the steering switch RS advances to position 10, the talking position, and as sequence switch 300 passes out of position 13 $\frac{1}{2}$ the steering switch RS is further advanced to position 11. Since now the district selector switch has moved to its overflow position and the sequence switch 300 is standing in position 15, a circuit is established for applying tone current to the right-hand winding of repeating coil 336 from the source of tone current 368, through the left-hand contacts of sequence switch spring 319 (15), lower right-hand winding of repeating coil 336, condenser 399, lower left-hand contact of spring 395 (15), upper left-hand contacts of spring 333 (14+15), upper right-hand contact of said spring (10+15), lower right-hand contact of spring 382 (15+18), upper left-hand contacts of said spring (13+15), right-hand alternate contacts of relay 390 and lower left-hand contact of sequence switch spring 314 (1 $\frac{1}{2}$ +18 $\frac{1}{4}$), to ground. This tone current is inductively transmitted over the calling subscriber's line through the left-hand windings of repeating coil 336, the supervisory relay 370 and the wipers 242 and 243 of the steering switch. The calling subscriber receiving this tone is apprised of the fact that it is impossible to obtain the desired connection at this time and therefore restores his receiver to its switchhook to release the connection. 105

What is claimed is:

1. In a telephone exchange system, a calling telephone line, a plurality of stations thereon, a message register for each station of the line, automatic switching means for extending a connection from the calling line, a circuit for operating the message registers, means common to a plurality of lines for testing the calling line to determine which station of the party line is calling, a switching device individual to the calling line controlled by said testing means for extending said circuit to the message register corresponding to the calling line, and means for closing said message register circuit to actuate said register. 110
2. In a telephone exchange system, a calling telephone line, a plurality of stations thereon, a message register for each station of the line, automatic switching means for extending a connection from the telephone line, a circuit for operating the message registers, means common to a plurality of lines for testing the calling line to determine which station of the party line is calling, electromagnetic means individual to the 115 calling line controlled by said testing means for extending said circuit to the message register corresponding to the calling line, and means for closing said message register circuit to actuate said register. 120
3. In a telephone exchange system, a calling telephone line, a plurality of stations thereon, a message register for each station of the line, automatic switching means for extending a connection from the telephone line, a circuit for operating the message registers, means common to a plurality of lines for testing the calling line to determine which station of the party line is calling, electromagnetic means individual to the 125 calling line controlled by said testing means for extending said circuit to the message register corresponding to the calling line, and means for closing said message register circuit to actuate said register. 130

calling line controlled by said testing means for extending said circuit to the message register corresponding to the calling line, and means for closing said message register circuit to actuate said register.

3. In a telephone exchange system, a calling line, a plurality of subscribers' substations on said line, a called line, automatic switching mechanism for establishing a connection between said lines, message registers associated with said calling line and individual respectively to said substations, means associated with the several substations for placing discriminatory test conditions on said calling line, means associated with said switching mechanism common to a plurality of lines and responsive to said test conditions, and means individual to said calling line and responsive to said last named means for selecting the message register corresponding to the calling substation.

4. In a telephone exchange system, a calling line, a plurality of subscribers' substations on said line, a called line, automatic switching mechanism for establishing a connection between said lines, message registers associated with said calling line and individual respectively to said substations, means associated with the several substations for placing discriminatory test conditions on said calling line, means associated with said switching mechanism common to a plurality of lines and responsive to said test conditions, means individual to the calling line controlled by said second mentioned means for selecting the message register corresponding to the calling substation, and means effective following the successful establishment of the connection for operating the selected register.

5. In a telephone exchange system, a calling line, a plurality of subscribers' substations on said line, a called line, a line finder switch and a series of selector switches for extending a connection between said lines, message registers associated with said calling line and individual respectively to said substations, a common operating circuit for operating said registers extending through a wiper of said line finder to the first switch of said series of selector switches, means associated with the several subscribers' substations for placing discriminatory test conditions on said calling line, means associated with said first selector switch responsive to said test conditions, electromagnetic means individual to the calling line controlled by said second mentioned means for connecting the message register corresponding to the calling substation to the common operating circuit.

6. In a telephone exchange system, a calling line, a plurality of subscribers' stations on said line, a called line, a line finder

switch and a series of selector switches for extending a connection between said lines, message registers associated with said calling line and individual respectively to said substations, a common operating circuit for operating said registers extending through a wiper of said line finder to the first switch of said series of selector switches, means associated with the several subscribers' substations for placing discriminatory test conditions on said calling line, means associated with said first selector switch responsive to said test conditions, electromagnetic means individual to the calling line controlled by said second mentioned means for connecting the message register corresponding to the calling substation to the common operating circuit, and means effective upon the successful establishment of the connection for operating the selected register.

7. In a telephone exchange system, a calling line, two subscribers' substations on said line, a called line, automatic switching mechanism for establishing connections between said lines, message registers associated with said calling line and individual respectively to said substations, a switching device individual to the calling line, means at one of said substations for placing a discriminatory ground potential upon one of the conductors of the calling line, means associated with said switching mechanism common to a plurality of lines and responsive to said ground potential for determining the position of said switching device to select the message register corresponding to the calling substation, and means effective upon the successful establishment of the connection for operating the selected register.

8. In a telephone exchange system, a calling line, two subscribers' substations on said line, a called line, automatic switching mechanism for establishing connections between said lines, means at one of said substations for placing a discriminatory ground test potential upon one of the conductors of the calling line, message registers associated with said calling line and individual respectively to said substations, a common operating circuit for said registers, switching means for associating one or the other of said registers with said operating circuit, a relay associated with said switching mechanism common to a plurality of lines and responsive to said test potential for controlling the operation of said switching means to connect the register to the common operating circuit corresponding to the calling station, and means effective upon the successful establishment of the connection for operating the selected register.

9. In a telephone exchange system, a calling line, two subscribers' stations on said

- line, a called line, automatic switching mechanism for establishing a connection between said lines, message registers associated with the incoming end of said calling line and individual respectively to said substations, means at one of said substations for placing a discriminatory ground test potential upon one of the conductors of the calling line when the substation is calling, testing means associated with said switching mechanism responsive either to said test potential or to an unstandard ground condition of said line, means individual to said calling line and controlled by said testing means operative upon the successful establishment of the connection for conditioning for operation the register corresponding to the calling line, means effective upon the release of the connection only when said line is found to be in a standard condition for operating the conditioned register, an alarm signal, and means for operating said alarm signal if said line is found to be in an unstandard condition.
10. In a telephone exchange system, a calling line, a plurality of subscribers' substations on said line, a called line, automatic switching mechanism for establishing a connection between said lines, message registers associated with said calling line and individual respectively to said substations, means at one of said substations for placing a discriminatory ground test potential upon one of the conductors of the calling line 35 when the substation is calling, testing means associated with said switching mechanism responsive to said test potential, means individual to the calling line controlled by said testing means for selecting the message 40 register corresponding to the calling line, connecting means operative prior to the completion of the connection for associating said testing means with said conductor of said calling line, means operative upon the successful establishment of the connection for conditioning the selected register for operation, means operative upon the restoration of the calling subscriber's receiver to its switchhook for reoperating 45 said connecting means to reassociate said testing means with said calling line for detecting an unstandard condition of said line, and means operative thereafter for operating the selected register if said testing 50 means finds said line in a standard condition.
11. In a telephone exchange system, a line, a plurality of stations thereon, a cut-off relay, a message register corresponding to each of said stations, a circuit for operating said message registers, and contacts controlled by said cut-off relay for switching any one of said registers to said circuit.
- In witness whereof, I hereunto subscribe 60 my name this 23rd day of November A. D., 1922.

FRANK S. IRVINE.

(OVER)

DISCLAIMER.

1,541,356.—*Frank S. Irvine, Huntington, N. Y.* MESSAGE-REGISTER SYSTEM. Patent dated June 9, 1925. Disclaimer filed January 11, 1928, by the assignee, *Western Electric Company, Incorporated.*

Herby enters this disclaimer to the said claims of said Letters Patent which are in the following words to wit:

“1. In a telephone exchange system, a calling telephone line, a plurality of stations thereon, a message register for each station of the line, automatic switching means for extending a connection from the calling line, a circuit for operating the message registers, means common to a plurality of lines for testing the calling line to determine which station of the party line is calling, a switching device individual to the calling line controlled by said testing means for extending said circuit to the message register corresponding to the calling line, and means for closing said message register circuit to actuate said register.

“2. In a telephone exchange system, a calling telephone line, a plurality of stations thereon, a message register for each station of the line, automatic switching means for extending a connection from the telephone line, a circuit for operating the message registers, means common to a plurality of lines for testing the calling line to determine which station of the party line is calling, electromagnetic means individual to the calling line controlled by said testing means for extending said circuit to the message register corresponding to the calling line, and means for closing said message register circuit to actuate said register.

“3. In a telephone exchange system, a calling line, a plurality of subscribers' substations on said line, a called line, automatic switching mechanism for establishing a connection between said lines, message registers associated with said calling line and individual respectively to said substations, means associated with the several substations for placing discriminatory test conditions on said calling line, means associated with said switching mechanism common to a plurality of lines and responsive to said test conditions, and means individual to said calling line and responsive to said last named means for selecting the message register corresponding to the calling substation.

“4. In a telephone exchange system, a calling line, a plurality of subscribers' substations on said line, a called line, automatic switching mechanism for establishing a connection between said lines, message registers associated with said calling line and individual respectively to said substations, means associated with the several substations for placing discriminatory test conditions on said calling line, means associated with said switching mechanism common to a plurality of lines and responsive to said test conditions, means individual to the calling line controlled by said second mentioned means for selecting the message register corresponding to the calling substation, and means effective following the successful establishment of the connection for operating the selected register.”

“7. In a telephone exchange system, a calling line, two subscribers' substations on said line, a called line, automatic switching mechanism for establishing connections between said lines, message registers associated with said calling line and individual respectively to said substations, a switching device individual to the calling line, means at one of said substations for placing a discriminatory ground potential upon one of the conductors of the calling line, means associated with said switching mechanism common to a plurality of lines and responsive to said ground potential for determining the position of said switching device to select the message register corresponding to the calling substation, and means effective upon the successful establishment of the connection for operating the selected register.

“8. In a telephone exchange system, a calling line, two subscribers' substations on said line, a called line, automatic switching mechanism for establishing connections between said lines, means at one of said substations for placing a discriminatory ground test potential upon one of the conductors of the calling line, message registers associated with said calling line and individual respectively to said substations, a common operating circuit for said registers, switching means for associating one or the other of said registers with said operating circuit, a relay associated with said switching mechanism common to a plurality of lines and responsive to said test potential for controlling the operation of said switching means to connect the register to the common operating circuit corresponding to the calling station, and means effective upon the successful establishment of the connection for operating the selected register.”

“11. In a telephone exchange system, a line, a plurality of stations thereon, a cut-off relay, a message register corresponding to each of said stations, a circuit for operating said message registers, and contacts controlled by said cut off relay for switching any one of said registers to said circuit.”
